CLAIM

I claim the ornamental design for a lighter, as shown and described.

DESCRIPTION

FIG. 1 is a rear elevational view of the lighter showing my new design;

FIG. 2 is a front elevational view thereof, the opposite side being a mirror image;

FIG. 3 is a right side elevational view thereof, the opposite side being as shown in FIG. 4;

FIG. 4 is a left side elevational view thereof, the opposite side being as shown in FIG. 3;

FIG. 5 is a top plan view thereof, the opposite side as shown FIG. 6;

FIG. 6 is a bottom plan view thereof; and,

FIG. 7 is a front elevational view showing the cap open.

CERTIFICATE OF CORRECTION

PATENT NO. : Des. 453,585 S
DATED : February 12, 2002
INVENTOR(S) : Robert F. Walker, Jr.

It is certified that error appears in the above-identified patent and that said Letters Patent is hereby corrected as shown below:

The title page should be deleted and substitute therefore the attached title page as shown on the attached page.

Delete drawing sheets 1-7, and substitute therefore the drawing sheets, consisting of Figs. 1-7, as shown on the attached pages.

Signed and Sealed this

Sixth Day of May, 2003

JAMES E. ROGAN
Director of the United States Patent and Trademark Office
